(57) **CLAIM**

The ornamental design for a front face of a portion of a wipes container, as shown and described.

DESCRIPTION

FIG. 1 is a perspective view of a front face of a portion of a wipes container showing our new design;
FIG. 2 is a front elevational view thereof;
FIG. 3 is a rear elevational view thereof;
FIG. 4 is a side elevational view thereof;
FIG. 5 is an opposite side elevational view thereof;
FIG. 6 is top plan view thereof; and,
FIG. 7 is a bottom plan view thereof.

The broken-lines are understood to represent portions of the article in which the claimed design is embodied, but which form no part of the claimed design.
